UNITED STATES PATENT OFFICE.

CHARLES W. LAPHAM, JR., OF PHOENIX, ARIZONA.

DESIGN FOR A JEWELRY PIN, BROOCH, OR SIMILAR ARTICLE FOR PERSONAL WEAR.

52,279.

Specification for Design.

Patented Aug. 20, 1918.

Application filed December 22, 1917. Serial No. 208,523. Term of patent 3½ years.

To all whom it may concern:

Be it known that I, CHARLES W. LAPHAM, Jr., a citizen of the United States, residing at Phoenix, in the county of Maricopa and State of Arizona, have invented a new, original, and ornamental Design for a Jewelry Pin, Brooch, or Similar Article for Personal Wear, of which the following is a specification, reference being had to the accompanying drawing, forming part thereof.

The figure is a front elevation of a pin, brooch or similar article for personal wear, showing my design.

I claim:

The ornamental design for a jewelry pin, brooch, or similar article for personal wear, as shown.

CHARLES W. LAPHAM, JR.
